Patented June 28, 1921.

UNITED STATES PATENT OFFICE.

ELLISWORTH A. HAWTHORNE, OF BRIDGEPORT, CONNECTICUT.

LAMP.

1,383,204.

Specification of Letters Patent. Patented June 28, 1921.

Application filed August 27, 1915. Serial No. 47,573.

To all whom it may concern:

Be it known that I, ELLISWORTH A. HAWTHORNE, a citizen of the United States, and a resident of Bridgeport, county of Fairfield, and State of Connecticut, have invented an Improvement in Lamps, of which the following description, in connection with the accompanying drawings, is a specification, like characters on the drawings representing like parts.

This invention relates to lamps, more particularly to electric lamps of the parabolic reflector type, and among other objects provides simple and effective focusing and switch devices therefor.

The character of the invention may be best understood by reference to the following description of an illustrative embodiment thereof shown in the accompanying drawings, wherein,—

Figure 1 is a vertical, longitudinal section of an electric lamp embodying the invention;

Fig. 2 on an enlarged scale, is a horizontal sectional detail showing the lamp-receiving focusing tube in plan;

Fig. 3 is a section taken on line 3—3 of Fig. 2;

Fig. 4 is a transverse section taken on line 4—4 of Fig. 3; and

Fig. 5 is a transverse section taken on line 5—5 of Fig. 3.

Referring to the drawing, the illustrative lamp shown therein as embodying the invention, comprises a casing 1 in which is mounted a reflector 3 shown herein as of parabolic form, although a reflector of a different type may be used if desired. The reflector may have a flange 5 threaded to the casing 1, and the open end of the reflector may be closed by a door 7 containing a glass 9, all substantially as shown in my Patent No. 1,203,618, Nov. 7, 1916.

An electric light bulb 11 may be introduced into the reflector centrally of the inner end thereof. To support the bulb its shell 13 is connected to a member typified herein as a tube 15 extending through registering apertures in the reflector and casing and across the chamber formed therebetween. The bulb shell 13 may be secured in said tube by diametrically opposed pins 17 entered into bayonet slots 19.

An important feature of the invention relates to means for adjusting the tube 15

axially for focusing the light, but without imparting rotative movement thereto, or distributing the electrical connections therewith. To accomplish this, the rear end of the tube 15 may have an enlargement 21 threaded into a sleeve 23 having a portion reversely bent to present a flange 25 overlapping a short collar 27 entered through the aperture in the casing and secured to the latter. The sleeve is free for rotation on the collar as a bearing, but is confined against movement axially thereof by the engagement of the reverse bend of the sleeve with the end of the collar, and by the engagement of an in-bent edge 29 of the sleeve flange with a circumferential shoulder 31 formed on the collar. The flange 25 may have its external surface knurled to facilitate the rotation thereof.

To prevent rotation of the tube 15 while it is adjusted in the direction of its axis for the focusing of the light, it is provided with diametrically opposed elongated slots 33 (Figs. 2, 3 and 5) adapted to receive lugs 35 (Fig. 2) projecting therein from the edge 30 of the reflector aperture.

When it is desired to focus the light it is merely necessary to grasp the knurled sleeve flange 25 and rotate the same. The threaded connection of the sleeve with the tube will cause the latter and the light to travel in or out relatively to the reflector according to the direction of rotation of the sleeve, but without imparting any rotative movement to the tube.

The lamp may be equipped with a supplemental electric light bulb 37 which is preferably adapted to provide a light of materially less intensity than that given by the bulb 11. The two lights may be used alternatively, the small bulb being used at times when the blinding glare of the large bulb is not desired. To contribute to the diminished light intensity effect of the small light, it preferably is located in the reflector out of the focus thereof. It is shown herein positioned a substantial distance from the center of the reflector and provided with a shell 39 threaded into a socket 41 formed by a flange bent outward from the reflector.

Next will be described the electrical connections for supplying current to the lights. To accomplish this, the tube 15 is provided with a filler 43 (Fig. 3) of rubber or other

appropriate insulation material. In one end of this filler is a recess receiving a usual spring-pressed contact pin 44 for engagement with the large light when introduced 5 into the tube. The filler is recessed to receive a slug 45 of brass or other appropriate conducting material adapted to be connected to the pin 44 by a screw 47 entered through an enlarged aperture in the tube and tapped 10 into the filler at one end of the slug 45. At the opposite end of said slug is a bore 49 containing a contact pin 51 normally urged outward by a helical spring 53 encircling said pin and confined against the head 15 thereof and the end of said slug.

The small light is connected by a wire containing cable 55 (Fig. 1) with a stud screw 57 entered through an enlarged aperture in the tube and tapped into a slug 59 20 of brass or other appropriate conducting material inserted in a recess in the filler. This slug has a bore 61 receiving a spring-pressed contact pin 63 similar to the contact pin 51 described.

25 A switch operating member herein in the form of a plug 65 of rubber or other insulation material is provided at one end with a flattened handle 67 and at its opposite end with a cylindrical portion 69 adapted to fit 30 in the outer end of the tube 15. A wire containing cable 71 may be entered into an axial bore 73 in the plug and be connected to a switch arm 75 (Fig. 4) of brass or other appropriate conducting material mounted on a 35 short sleeve 77 and set in a recess in the face of the plug.

The plug 65 is adapted to be turned to cause the switch arm 75 to engage the large light contact pin 51, the small light contact 40 pin 63, or neither of them, as desired.

To determine the different positions of adjustment of the plug, it may be provided with diametrically opposed pins 79 (Fig. 4) 45 projecting outward into diametrically opposed slots 81 in the tube 15. Each slot has a notch 83 at one end thereof, a notch 85 at the opposite end thereof, and a notch 87 midway between the end notches.

When it is desired to turn the plug to 50 shift the switch, the plug is pushed inward somewhat against the resistance offered by the springs of the contact pins 51 and 63, thereby causing the pins 79 to move out of the notches which they have occupied. Then 55 the plug may be readily turned to slide the pins along the slots to any of the other notches as desired.

When the pins 79 are seated in the notches 83, the switch 75 will engage the contact pin 51 and complete the circuit to the large light.

When the pins 79 are seated in the notches 85, the switch 75 will engage the contact pin 63 and complete the circuit to the small light.

65 When the pins 79 are seated in the notches

87, the switch 75 will not engage either of the contact pins 51 and 63 and the circuits to both lights will be broken.

It will be observed the turning of the switch plug does not in any way affect or 70 disturb the position of the large light carrying tube 15, and that the axial adjustment of the tube for focusing does not in any way disturb the switch. Thus, each is independent of the other, while the elements 75 thereof are formed and assembled in a very simple, compact and convenient organization.

The slots 81 are of short length and limit the rotative adjustment of the switch plug 80 to an arc of short extent in effecting all of the adjustments of the switch. Consequently, it is impossible materially to twist the cable entered into the switch plug and the likelihood of the loosening of the cable from the 85 plug is reduced to a minimum.

The collar flange 25 overlaps and co-operates with the collar 27 to form a housing which desirably conceals and protects the electrical connections and the screw connection 90 of the sleeve with the tube. They also add to the finished, neat appearance of the lamp.

The cable 55 and the small light are both 95 inclosed completely within the casing, thereby leaving the exterior surface of the casing smooth and uninterrupted.

The lights may be conveniently introduced and positioned in their proper places through the end of the casing on the open- 100 ing of the door.

Having described one illustrative embodiment of the invention without limiting the same thereto, what I claim as new, and desire to secure by Letters Patent, is:

1. In a lamp, a casing, a reflector within the casing, a non-circular aperture in the reflector, a member fitting said aperture and extending between the reflector and the casing, a sleeve mounted in said casing and having screw engagement with said member, a primary light carried by said member, a secondary light within the reflector, electrical connections for the latter light disposed between the reflector and casing and connected with said member, a switch member carried by said member exteriorly of the casing and rotatable about an axis substantially aligned with the longitudinal axis of said member selectively to control circuits to 110 said lights.

2. In a lamp the combination of a casing with a reflector defining a space between them, separate main and auxiliary lights in said reflector, a member partly housed in 115 said space and having a socket at its forward end receiving the main light, an electrical connection between said member and the auxiliary light, switching mechanism in said member and a switch operating handle 120

also carried by said member for operating said mechanism selectively to make and break the circuits to said lights, said member having means for determining the positions of adjustment of the handle.

3. In a lamp, the combination of a casing with a reflector, main and auxiliary lights therein, a non-rotative tube adjustable axially to focus the main light, electric contacts in said tube for said lights respectively, a plug having a switch for engagement with said contacts, a slot in said tube having notches therein, and a pin projecting from said plug adapted to seat in said notches.

4. In a reflecting electric lamp, the combination with a reflector carrying casing; of an electric lamp bulb; a shell carrying the lamp bulb at its front end; switching contacts within the casing for cutting the lamp in and out of circuit; a plug within the casing and coupled with the shell and carrying one of said contacts and movable with respect to the shell; and means operable from the exterior of the casing for effecting relative motion between the plug and shell to cut the lamp in and out of circuit and for effecting movement of the shell and the lamp bulb in and out to adjust the lamp bulb with respect to the reflector.

5. In a reflecting electric lamp, the combination with a reflector carrying casing; of an electric lamp bulb; a shell carrying the lamp bulb at its front end; engageable eccentrically disposed switching contacts within the casing for cutting the lamp in and out of circuit; a plug within the casing and mounted to turn in the shell and coupled therewith and carrying one of said contacts; and means operable from the exterior of the casing for turning the plug to cut the lamp in and out of circuit and for effecting movement of the shell and the lamp bulb in and

out to adjust the lamp bulb with respect to the reflector.

6. In a reflecting electric lamp, the combination with a reflector carrying casing; of an electric lamp bulb; a shell carrying the lamp bulb at its front end; switching contacts within the casing for cutting the lamp in and out of circuit; a plug within the casing and coupled with the shell and carrying one of said contacts and movable with respect to the shell; means operable from the exterior of the casing for effecting relative motion between the plug and shell to cut the lamp in and out of circuit; and a screw engaging the casing and being connected with the shell and being operable from the exterior of the casing to move the shell in and out to adjust the lamp bulb with respect to the reflector.

7. In a reflecting electric lamp, the combination with a reflector carrying casing; of an electric lamp bulb; a shell carrying the lamp bulb at its front end; engageable eccentrically disposed switching contacts within the casing for cutting the lamp in and out of circuit; a plug within the casing and mounted to turn in the shell and coupled therewith and carrying one of said contacts; means operable from the exterior of the casing for turning the plug to cut the lamp in and out of circuit; and a screw engaging the casing and being connected with the shell and being operable from the exterior of the casing to move the shell in and out to adjust the lamp bulb with respect to the reflector.

In testimony whereof, I have signed my name to this specification, in the presence of two subscribing witnesses.
